UNITED STATES PATENT OFFICE.

SERAFIN RONCERO, OF FRAMINGHAM, MASSACHUSETTS.

SAFETY SYSTEM FOR STEAM-BOILERS.

1,283,312.

Specification of Letters Patent. Patented Oct. 29, 1918.

Application filed May 7, 1917. Serial No. 166,316.

To all whom it may concern:

Be it known that I, SERAFIN RONCERO, a citizen of the United States, and a resident of Framingham, county of Middlesex, and 5 State of Massachusetts, have invented an Improvement in Safety Systems for Steam-Boilers, of which the following description, in connection with the accompanying drawings, is a specification, like characters

10 on the drawings representing like parts.

This invention relates to safety systems for steam boilers and its object is to provide novel means, acting automatically, to control the action of the feed water pump to keep 15 the water at a substantially constant and safe level in the boiler.

Referring to the drawings of the embodiment of my invention illustrated and described herein:

20 Figure 1 is a diagrammatic view of one arrangement of the elements of my invention in connection with a steam boiler, the pump controlling means being shown somewhat enlarged for clearness.

25 Fig. 2 is a detail of the emergency valve for drawing water from the boiler in case the usual means fails; and

30 Fig. 3 is a detail of the danger alarm valve for sounding an alarm when the water falls below the danger point.

Referring first to Fig. 1, a conventional type of upright steam boiler is represented at 1, which is connected by a pipe 2 with a feed pump 3 which is actuated with steam supplied with a pipe 4.

For controlling the supply of steam to the pump 3, and consequently the action thereof, I have invented novel means.

The boiler is provided at a suitable point 40 with a valve chamber 5 of suitable material as metal herein of cylindrical type, which is connected with the boiler by a pipe 6 above the normal water line 7 and below the normal water line by a pipe 8. Each pipe may 45 be provided with a usual valve 9.

In the valve chamber, Fig. 1, is a float 10 of suitable material as wood or cork, carrying at its upper end a valve stem 11 which seats in the lower end of a pipe 12. The

valve is normally kept closed with the water 50 at normal level.

The pipe 12 is supplied with a usual valve 13 and runs to a pipe or cylinder 14 having a stuffing box 15 at one end and carried by any suitable support as 16. This cylinder 55 is shown somewhat enlarged for purpose of clearness.

Within the cylinder 14, Fig. 1, is a plunger 17 having a reduced section 18 which is received in a cylinder or pipe 19 also having a 60 stuffing box 20, and carried by a suitable support as 21, on the base 16 referred to. For operating the pump I provide a novel means which is as follows:

The steam pipe 4 is provided with a valve 65 22 having a seat 23, cover 24 therefor and chamber 25. The cover may be secured to the seat conveniently by bolts 26.

The chamber 25 is connected by a pipe 27 with the steam space of the boiler 1. The 70 valve chamber contains the valve 22 having a port 28 adapted to register with the port 29 in the seat 23 and thus controls communication with the pipe 4. For operating the valve 22 I provide a rack 30 in mesh with a 75 segmental gear 31 on the rock shaft 32.

The rock-shaft 32 is worked by a toggle-like device comprising an arm 33 loosely pivoted to one of herein a pair of levers 34 pivoted, in turn, to a suitable support as a 80 collar 35 on the pipe 27. The opposite ends of the levers 34 are suitably connected with the plunger 18, as by a pivot and slot connection with a cross-head 35' thereon. The cylinder 19 is also connected by a pipe 36 85 with the steam pipe 27.

The method of using my invention is as follows: The normal water line in the boiler is indicated at 7 and at this point it supports the float 10 and its valve stem in 90 position to close the valve in the pipe 12. If the water falls substantially below this line 7 the float will fall and open the valve in pipe 12 permitting steam to flow through pipe 12 to the cylinder 14. The pressure of 95 steam on the end of the plunger will force it outward causing the toggle levers 34 to rock the shaft 32 and slide the valve 22 to the

right, Fig. 1, so that its port 28 will register with the port 29 in the valve seat.

The opening of the valve permits steam from pipe 27 to flow through pipe 4 to the 5 pump 3, actuate it, and force water into the boiler. When the water in the boiler rises to normal level it raises the float 10, closes the valve in pipe 12 and shuts off the supply of steam from that source for the plunger 10 17 and pump 3.

When the pressure of steam on the plunger 17 is thus cut off the pressure of the steam on the opposite end of the plunger 18 supplied by means of pipe 36 will force the 15 plunger 17 inwardly again and thereby close the valve 22 and stop the pump.

In this manner the pump is automatically operated as needed to keep the water at substantially normal level.

20 As a precaution in case of accident to the foregoing pump controlling means, I provide the boiler also with a similar emergency float valve 37, Fig. 2, in a reversed position, the chamber for which is similarly connected 25 with the boiler by pipes 38, 39.

Normally the water does not support this valve and it remains closed. If, however, the water rises to an abnormal level then it opens the valve 37 and permits water to flow

30 from the boiler through pipe 39 and thus relieve the boiler and permits the valve 37 to again seat itself.

A similar valve alarm 40, Fig. 3, is also provided for the relief of steam pressure. 35 Ordinarily the water will hold the valve 40 closed but if it falls to a dangerous point it will cause the valve to open and thus permit steam to escape by means of pipe 41 and blow a whistle, if desired, to attract the attention of the fireman.

While I have shown herein one embodiment of my invention, it will be obvious that the construction may be modified in many detail respects within the spirit of the invention and scope of the appended claims.

Claims:

1. An automatic water regulator for steam boilers, comprising a pump having a water connection with the boiler, and also a steam 50 connection with the boiler, a slide valve in said steam connection, actuating means for the valve, and a plurality of steam connections between the boiler and the valve actuating means, one connection providing a constant steam pressure and another connection 55 an intermittent steam pressure.

2. An automatic water regulator for steam boilers, comprising a pump having a water connection with the boiler, and also a steam 60 connection with the boiler, a slide valve in said steam connection, actuating means for the valve, a plurality of steam connections between the boiler and the valve actuating means, one connection providing a constant

steam pressure and another an intermittent 65 steam pressure, and a valve in one of said steam connections between the boiler and the valve actuating means positively controlling the operation of the valve actuating means in one direction only.

3. An automatic water regulator for steam boilers, comprising a pump having water connection with the boiler, a steam connection also with the boiler, a slide valve in the steam connection, a two-diameter plunger 75 for actuating the valve and a steam connection between the boiler and each of the plunger cylinders, one connection providing a constant steam pressure and another an intermittent steam pressure.

4. An automatic water regulator for steam boilers, comprising a pump having water connection with the boiler, a steam connection also with the boiler, a slide valve having a port in the steam connection, normally 85 closed, a two-diameter plunger for actuating the valve, a cylinder for each diameter of the plunger at opposite ends thereof, and a separate steam connection between the boiler and each cylinder, one connection providing 90 a constant steam pressure and another an intermittent steam pressure.

5. An automatic water regulator for steam boilers, comprising a pump with a water connection with the boiler, a steam connection also with the boiler, a valve in the steam connection, a two-diameter plunger, a case for each diameter of the plunger each having a steam connection with the boiler, slide valve in the steam connection between the 95 pump and boiler and a toggle for actuating said valve.

6. An automatic water regulator for steam boilers, comprising a pump with a water connection to the boiler, a steam connection 105 also to the boiler, a valve in the steam connection, a two-diameter plunger, a case for each diameter of the plunger having a steam connection with the boiler, means for controlling the action of the valve in the pump steam connection with the boiler by said plunger, a water pipe leading from the boiler, and an automatically operating valve in said pipe adapted to be opened by the water in the boiler upon failure of the valve 115 in the steam connection to operate.

7. A feed pump regulator comprising a float chamber, a float valve therein, a steam connection adapted to connect the float chamber with the pump, a slide valve in said 120 connection, and valve actuating means comprising a multi-diameter plunger and connections between the plunger cylinders and the boiler providing varying degrees of pressure on the different plunger diameters.

8. An automatic water regulator for steam boilers, comprising the pump 3, pipe 2 connecting the same with the boiler, steam pipe

27 leading from the boiler, slide valve 22 with rack 30 in said steam pipe, connection 4 between the pump and said valve, piston cylinders 14, 19 with pistons therein, pipes 5 12, 36 connecting the cylinders respectively with the boiler, the former connection providing constant, and the latter connection providing intermittent steam pressure, valve

operating members 33, 34 with gear 31 connecting the valve and one of said pistons, 10 and a float chamber 5 with float 10 therein connecting the pipe 12 with the boiler.

In testimony whereof, I have signed my name to this specification.

SERAFIN RONCERO.
